UNITED STATES PATENT OFFICE.

CHARLES THOMAS KINGZETT, OF CHISLEHURST, ENGLAND.

GOLF-BALL.

SPECIFICATION forming part of Letters Patent No. 734,462, dated July 21, 1903.

Application filed September 2, 1902. Serial No. 121,811. (No model.)

To all whom it may concern:

Be it known that I, CHARLES THOMAS KINGZETT, chemical manufacturer, a subject of the King of Great Britain, residing at Elmstead 5 Knoll, Chislehurst, in the county of Kent, England, have invented a certain new and useful Improvement in Golf-Balls, of which the following is a specification.

According to my invention I construct golf-balls or portions of golf-balls of several alternating layers of gutta-percha and india-rubber or of other similar slightly and highly elastic substances. By this means the elasticity derived from the partial use of rubber 15 is well distributed throughout their entirety and is not confined to one particular part.

In balls with a core of india-rubber thread or sheet the core really constitutes a hard although elastic core, and the coating of gutta-percha being only about one-eighth inch thick every impact from the edge of an iron club is felt severely, and in the end the shell is cut through to the core or cracked, and then the ball is useless. Not so in my balls. The 25 impact is communicated in a wave-like manner from layer to layer. In other words, they are better cushioned and more continuous in nature, so that after the blow the balls more easily recover their original shape. It follows that my balls wear better and are easily remade by merely heating and remolding or, at worst, by adding a thin coating of gutta-percha. My balls putt well, for by reason of the elasticity being better diffused they do 30 not jump about so much when coming in contact with irregularities on the ground, as do balls whose elasticity is "concentrated," so to speak, in the core of elastic thread or elastic sheet, respectively.

40 In the drawings annexed I have illustrated three ways in which such balls may be made.

Figure 1 represents a sheet of gutta-percha, say, about one-sixteenth inch thick; Fig. 2, a similar shorter and narrow sheet of india-rubber. Fig. 3 is a longitudinal section of the same after they have been placed one over the other and then rolled together, so as to form a cylindrical roll. Fig. 4 shows a section of such cylindrical roll after its ends have 45 been roughly closed in by hand and the whole brought to an approximately spherical form. Fig. 5 shows an exterior view of the roll after 50 it has been compressed in a mold to bring it to a truly spherical form. Fig. 6 shows a section of a smaller ball formed in this way in- 55 cased in an outer casing of gutta-percha. Fig. 7 shows an india-rubber ball surrounded by a roll of gutta-percha and india-rubber in alternating layers, the roll being shown in longitudinal section. Fig. 8 shows a section 60 of same after the ends of the roll have been roughly closed in by hand and the whole brought to an approximately spherical form. Fig. 9 shows an elevation of the same after it has been compressed in a mold and brought 65 to spherical form. Fig. 10 shows the same after it has been inclosed in an outer casing of gutta-percha, the casing being shown in section. Fig. 11 shows a number of alternating sheets of india-rubber and gutta- 70 percha placed one over the other. Fig. 12 shows a cylinder punched out from such pile of alternating sheets. Fig. 13 shows this cylinder compressed to a spherical form and inclosed in an outer casing of gutta-percha. The 75 sphere is shown in elevation and the casing in section.

Preferably I place a strip of sheet india-rubber *a* onto a sheet of gutta-percha *b* of greater width and length and roll them up 80 together when more or less heated to form a cylindrical roll, with a gutta-percha exterior surface and with the side edges of the gutta-percha sheet protruding outward beyond the side edges of the rubber sheet, as illustrated 85 in Fig. 3. The ends of the cylindrical roll are then when the roll is heated closed in by hand, so as to bring it approximately to a spherical form, which may then be further compressed by a suitable mold; or, as illustrated 90 in Fig. 6, a smaller ball *d* may be formed in this way and inclosed in an outer casing of gutta-percha *c*, two hemispherical cups of gutta-percha being first molded and placed over the smaller ball and the whole then compressed together; or, again, the folds may be manifold although alternating—that is to say, around the core may be wound, under tension or otherwise, several layers or folds of first the one substance and then the other, 95 and so on; or, as illustrated in Figs. 7 to 10, a spherical core *e*, of india-rubber or other material, may have a sheet of gutta-percha and a sheet of india-rubber wound around it, so 100

as to form a cylindrical roll and the ends of this roll then closed in to form a cylindrical ball, which may then be incased in an outer casing of gutta-percha; or this core may be 5 cylindrical, which will render the rolling of the sheets upon it very easy; or, as illustrated in Figs. 11 to 13, a spherical core of alternating layers (not rolled) of india-rubber and gutta-percha may be inclosed within 10 an outer casing of gutta-percha.

I do not herein claim the method of making the balls herein shown and described, as such claims are made in my application for patent, Serial No. 141,875, filed February 4, 15 1903, and in my application, Serial No. 158,358, filed May 22, 1903.

Inasmuch as the rubber strips are hot and not under tension while being rolled, they are not under tension or are under very low tension 20 in the completed ball.

What I claim is—

1. A ball having in its composition a plurality of elastic layers of india-rubber which are unstretched or under low tension and 25 each separately inclosed between layers of gutta-percha.

2. A ball having its inner portion composed

wholly or partially of alternate layers of gutta-percha and of india-rubber which are unstretched or under low tension and having 30 such inner portion inclosed in an outer envelop of gutta-percha.

3. A ball the inner portion of which is wholly or partially of india-rubber strip wound into a roll together with a strip of 35 gutta-percha and molded into spherical form and having such inner portion inclosed in an outer casing of gutta-percha.

4. A ball the inner portion of which is composed wholly or partially of alternate strips 40 of india-rubber and gutta-percha wound up together into a roll and in which the india-rubber strip is throughout its length inclosed in a sheath of gutta-percha.

5. A ball having in its composition a plurality of elastic layers of india-rubber, each separately inclosed between layers of gutta-percha which layers of gutta-percha are themselves all united to an outer envelop of gutta-percha.

CHARLES THOMAS KINGZETT.
